UNITED STATES PATENT OFFICE.

JOHN F. STEWARD, OF PLANO, ILLINOIS.

GRAIN-BINDER.

SPECIFICATION forming part of Letters Patent No. 272,597, dated February 20, 1883.

Application filed October 20, 1880. (Model.)

To all whom it may concern:

Be it known that I, JOHN F. STEWARD, a citizen of the United States, residing at Plano, in the county of Kendall and State of Illinois, have invented new and useful Improvements 5 in Grain-Binders, of which the following is a full description, reference being had to the accompanying drawings.

Figure 1 is a front elevation; Fig. 2, a view 10 taken from the outer side of the machine, showing in elevation a portion of the slotted wall of the grain-receptacle and the holding and cutting mechanism; Fig. 3, an inverted plan view of the holder; Fig. 4, a plan view, 15 partly in section, of the knotter and its operating mechanism; Fig. 5, an inverted plan view of part of the holder; Fig. 6, a view of the camway for operating the movable jaw of the tyer, and Fig. 7 a view showing the position 20 of the cord at completion of the knot.

My improvements are adaptable to many forms of grain-binders now in use. As shown, they are adapted to that class of machine in which the binding mechanism is attached to the side 25 of the harvester, the grain being delivered over the drive-wheel into the binding-receptacle and against the cord leading from the cord-holder to the binding-arm. The devices shown are better suited to that class of binders 30 in which the gavel is compacted by special parts, independent of the compressing and binding mechanism, and to those using twine as binding material, yet certain parts may be employed in machines using wire.

The invention consists in such an arrangement 35 of the twine-holding mechanism that its parts shall automatically conform to variations in the size of twine, in so constructing the holding mechanism that it may take up in 40 seizing the twine an amount in length sufficient to form the knot, and in so regulating its movements that the same may be paid out as required by the tyer, and in an improved device for supporting the twine and dropping 45 the same when the knot is tied.

In the drawings, A is a wheel bearing on its rim the cam *a* for operating the knife and twine-holder, and on its side the cog-segments *b* and *c*, the delay-surfaces *d* and *e*, and the 50 cam *f*.

B is the pivot or shaft of the wheel A.

C is a support for the tyer and holder, mounted loosely upon the shaft B, so that the same may revolve therein.

D is a vibrating needle provided with an 55 extension, *g*, which I describe and claim in another application now in the Patent Office. The needle is keyed to the shaft E and receives its vibrating motion therefrom.

F is a lever or arm designed to carry the 60 bundle so low that the cord surrounding the same will be drawn by the needle well into the tyer. This lever is pivoted on a stationary part of the binder at *k*.

G is the tyer, its jaw *i* being a continuation 65 of the stem *m*, which slides in a slot in the shaft *G'* of the tyer, and which is provided with the roller *n*. This roller moves in the cam-groove *o*, made in the bearing of the tyer-shaft, thus giving the jaw an opening and closing 70 movement.

H is a cord-directing hook pivoted at *H'* in a standard on the support C and at *H''* in the plate I. It is swung at the proper time by means of the cam *f* coming in contact with the 75 roller *h* on the arm *h'*.

I is a plate separating the tying mechanism from the accumulating grain, and also forming a support for other parts. It is provided with a slot, through which the needle, after piercing 80 the grain, enters to carry the twine to the tyer, and to allow the band to be pulled down to draw the knot off from the tyer.

J is a lever for actuating the holding and cutting devices. It is provided with the anti-friction rollers *q* *q'*, spanning the rim, and the cam *a* of the wheel A is pivoted at *r*, and its lower extremity engages a notch in the slide K of the cord-holder.

L is a knife for severing the twine attached 90 to the said slide.

The cord-holding device is composed of the slide K, cheek *s*, and arm *t*, the latter being pivoted on the pin *w* in the support *u*.

v is a flat spring resting beneath the pivot 95 and giving it a slight pressure upward.

The operation of my holder is as follows, beginning with the parts K and *t*: In Fig. 5 they are shown in the position they are when the twine, a section of which is shown at *f'*, Fig. 5, is drawn within their reach. The rotation 100 of the wheel A imparts a reciprocating motion

to the slide K through the instrumentality of the cam *a* and lever J, the two rollers *q* spanning the rim of said wheel. The slide K is first carried in the direction indicated by the arrow in Fig. 5. The arm *t* will be turned on its pivot *w* (by the pin *x*, which is fixed to the slide K) to the position shown in Fig. 3, and the twine will be carried by the hook *t'* on the arm *t* into the notch on the slide K. The twine is doubled over the part forming the side of the notch in the slide K, and is carried between the sides of said slide and the arm *t* and cheek *s*, as shown in Fig. 2. The knife L, moving, as it does, with the slide K, severs that part of the twine extending between the holder and knot. Let it be understood that in my method of holding the twine but one strand is held at a time; that the held end *f*³, Fig. 7, is released as soon as the knot is tied; that it is the other ply of the twine (that coming through the eye of the needle) which is severed at *f*², Fig. 7, after the twine has been carried by this slide K between the holding parts. When the slide is moved to its place the needle rises and draws the twine up around the hook *t'* of the arm *t*, and it will be understood that, the said part being free to move upward, any strain put upon the upward-drawn twine will have the effect of drawing the holding parts closer together and pinch the twine the harder between them. In the ascent of the needle the twine is drawn across the receptacle, as shown by the dotted line in Fig. 1, the part nearest the holder being laid into the hook of the tyer while in its first position of rest. After the accumulation of the next gavel the descent of the needle carries the twine around the gavel and lays the part to be tied into the hook of the tyer. The wheel A moving in the direction indicated by the arrow in Fig. 1, the segment *b* is engaged with the pinion of the tyer, and it is given a revolution and a half in the direction indicated by the arrow in Fig. 1. A revolution only is necessary to complete the knot; but the movement continues for a half-revolution farther, so as to have the point of the tyer rest for a moment directed toward the bundle, so that when the latter falls away the knot will be drawn off the point of the tyer. The segment C engages with the teeth of the pinion, and gives the tyer another half-revolution, leaving it in its state of rest as shown in Fig. 1. The delay-surfaces *j* upon the end of the pinion slide upon the locking-faces *d* and *e* of the wheel A and retain the pinion in position while it is between the segments.

Although I operate the jaw of the tyer differently from others, its handling of the twine and forming the loop is that in common use, and is well shown and described in the patents of J. Behel, February 16, 1864, S. D. Locke, February 11, 1870, and others. When by a revolution of the tyer the twine is formed around it and the part to be drawn through the knot is laid between the jaws, the roller

on the sliding jaw, running in the cam-groove *o*, causes the jaw to slide and close, which it does a little before the tyer reaches its position of rest for the discharge of the knot. The bundle falls, drawing the loop off the point of the tyer and over the loop still held between the jaws, and tightening the knot. Upon the engagement of the segment *c* with the pinion the tyer makes its final half-revolution, and by means of the cam-groove *o* the jaw of the tyer is permitted to open and let the loop escape. The cam-groove *o* is represented in Figs. 4 and 6. Just before the tyer is in its first state of rest the arm *t* of the holder is open for an instant, as shown in Fig. 5. The hook *t'* then is caused to carry the twine into the notch in the slide K, which then moves and carries the twine in between the clamping-surfaces, and the knife L severs the twine at *f*², Fig. 7, as before described. The amount of twine required to encircle the tyer in forming the knot is not drawn through the holder, and thus injured; but the slide K moves at the proper rate and time to allow the tyer to have what is needed. Bearing in mind that the upper side of the arm *t* is channeled or cut away where the twine lies between it and the slide K, as shown in dotted lines, and hence that the twine is held only by pressure between the slide K and cheek *s*, it will be understood that, if the slide K is slowly moved to the left, the twine (if slight stress be applied) will pay out in the direction of the tyer—that shown by the arrow in Fig. 2. As the slide K withdraws, all that part of the twine released from pressure between it and the cheek *s* will be free to render around and upward. As the needle descends through the grain the compressor will move a little in advance and carry the bundle so low that the twine will be carried into the hook of the tyer and be drawn out at such an angle as to be sure of lying in place. This movement of the compressor will be understood by reference to Fig. 1. The arm F being pivoted to a part of the frame-work at a distance from the shaft E, as the needle rises and falls the link *h'* will be swung on the pivot *i'*, and when the needle is thrown upward the arm F will lie parallel with the needle. A return movement of the needle will reverse the swing and carry the arm F to the position shown in Fig. 1. While the knot is being made the twine must be held in a certain relation to the tyer. This is done by the hook H, which is always retained in the position shown in Fig. 2, except when the knot is finished, when the cam *f* on the wheel A passes, so that the roller *h* can no longer tread on it, and the hook H is permitted to swing and allow the knot to fall, and thus escape. The guide U also helps to retain the twine in position in relation to the tyer.

The inner side of the receptacle is shown at T, Fig. 1, and the passage of the grain is limited between it and the plate I.

What I claim as new is—

1. The combination of the tying mechanism

and holding mechanism with the slide K and mechanism for moving it to close upon the twine and to take up any length of said twine that may be required to form the knot, and to withdraw at the proper rate and proper time in relation to the movement of the tying mechanism to pay out the amount thus taken up, substantially as and for the purpose set forth.

2. The combination, with the cheek s and the slide K, of the arm t to assist in grasping the twine and to direct the pressure caused by draft upon the twine, so as to compress its end

5 between the said parts K and s, substantially as shown and described.

3. The combination of the wheel A, having 15 the cam-rib a, with the slide K, cheek s, and intermediate operating mechanism for taking up, holding, and paying out the length of twine required to form the knot, substantially as described.

JOHN F. STEWARD.
